UNITED STATES PATENT OFFICE.

WILLIAM CLARK KIRK, OF CHATTANOOGA, TENNESSEE.

COLUMN-LATHE.

SPECIFICATION forming part of Letters Patent No. 743,728, dated November 10, 1903.

Application filed December 15, 1902. Serial No. 135,306. (No model.)

To all whom it may concern:

Be it known that I, WILLIAM CLARK KIRK, a citizen of the United States of America, and a resident of Chattanooga, county of Hamilton, State of Tennessee, have invented certain new and useful Improvements in Column-Lathes, of which the following is a specification, reference being had to the accompanying drawings, in which—

- 10 Figure 1 is a side elevation of one half of a lathe constructed according to my invention, the other half being a duplicate of that shown and being omitted for better illustration; Fig. 2, an end elevation of the lathe, the bed-beams being shown in section; Fig. 3, an elevation of the rear end of the head-stock, a portion of the housing being broken away; Fig. 4, a vertical longitudinal sectional view of a portion of the head-stock, showing the 15 devices for adjusting the shaft of the head-stock longitudinally to regulate the depth of cut; Fig. 5, a face view of the tool-carrying plate or bar; Fig. 6, a transverse section thereof on the line 6 6; Fig. 7, a vertical sectional view of one of the tool-holders, taken 20 on the line 7 7 of Fig. 8; Fig. 8, a face view of one of the tool-holders; Fig. 9, a detail view showing the adjustable arm carrying the removable feed-pin.
- 25 This invention has reference to that class of lathes especially adapted for turning or planing off the end faces of columns, pipes, column-bases, I-beams, and like heavy articles and which consists generally of a suitable bed-frame, a pair of head-stocks slidably mounted thereon and carrying the facing tools, means for driving the shafts of the head-stocks, and two or more work supports or clamps adjustably supported intermediate 30 the head-stocks and adapted to rigidly and accurately support the work while the opposite ends thereof are being turned off; and the object of the invention is to simplify and improve the structure in various respects, as 35 more fully hereinafter set forth.

Referring to the drawings, the letter *a* designates the I-beams, which, together with the transverse connecting-brackets *b*, form the bed of the apparatus. Upon this bed are 40 mounted two head-stocks, only one of which

is shown in the drawings. This head-stock consists of a frame *c*, extending across and supported upon the I-beams. To clamp this head-stock at the desired point on the bed, bolts *d* are mounted in lateral lugs formed 55 integral with the frame of the head-stock and projecting out beyond the edges of the I-beams. The lower end of each of these bolts is bent inward, so as to engage under the outer flange of the I-beams, and upon the 60 upper end of the bolt is screwed a fastening-nut *e*. Four rollers *f* are employed, each being journaled to an eccentric *g* on the inner end of a short horizontal shaft *g*, journaled in the frame, the outer end of this shaft being 65 provided with a handle *h*. By turning up these handles the rollers will be caused to impinge against the I-beams, and the head-stock will be slightly raised from the beams, in which position it may be readily moved 70 along the bed without undue friction. One of the clamping-bolts *d* is mounted at each corner of the head-stock, as shown, and one of the rollers is mounted adjacent to each 75 clamping-bolt.

Journaled in suitable bearings in the frame *c* is the horizontal shaft *i*, on the forward end of which is rigidly secured the chuck-carrying bar or plate *j*, which is provided on its face with the usual way for the tool chucks 80 or carriers *k*, two of which are employed, as usual, one being arranged at each side of the center. To adjust these tool-chucks along the way to and from the center, a pair of radial screws *l* are employed, as usual, the ends of 85 these screws projecting beyond the ends of the bar *j* and carrying the usual star-wheel *m*. Each tool-chuck is provided with a pair of square sockets *n* for the reception of the tools, and, as shown in dotted lines in Fig. 5, these 90 sockets are so placed in each block that the sockets of one chuck are at opposite sides of the central line of the chuck-bar and shaft from the sockets of the other chuck, the inner walls of these sockets being directly in line 95 with each other and with the center of the shaft of the head-stock. To bring the tool-sockets in this position with respect to each other, they are arranged at one side of a line drawn through the center of the chuck, as 100

shown in Fig. 8, the dotted line *o* indicating the central line of the chuck. The object in thus disposing the tool-sockets is to bring the cutting edges of the tools in line with each other and in line with the center of the head-stock, whereby the cutting edges of the tools will travel to the center, and thereby avoid leaving a projection of metal at the center of the work being operated upon. To automatically adjust the tool-chucks along the chuck-bar as the head-stock rotates, a pin *p* is supported in a bracket *q*, adjustably attached to one of the I-beams, this bracket being so positioned that the pin *p* will lie in the path of the star-wheel *m*, so that as each star-wheel passes the pin it will be slightly rotated, and thereby through the medium of the screw adjust the tool-chuck. In order that the feed may be stopped readily, the pin *p* is made removable from its socket on the bracket, whereby the feed may be stopped without adjusting the bracket out of the path of the star-wheels. The other end of shaft *i* passes through the sleeve-like hub *r* of a worm-gear *s* and carries at its extreme end a threaded axial extension *t*, said sleeve-like hub *r* being journaled in one of the standards of the frame *c* and being held against endwise movement therein by means of suitable nuts *u*, threaded on the end of said sleeve-like hub. A key *s⁴* is dovetailed into the hub of gear *s* and adapted to work in a keyway in shaft *i*, whereby the shaft may be shifted endwise independently of the gear, but will be compelled to rotate with it. Bolted to the outer face of the worm-gear is a shell or casing *v*, through a central opening in which the screw extension *t* passes. Threaded on the extension *t* is a nut *w*, which is provided with a hand-wheel for readily turning it and which has its inner end extended into the central opening in the shell *v* and provided with a flange *x* to engage the edge of said opening on the inner side of the shell. By this arrangement the shaft *i* may be adjusted endwise in its bearings independent of the worm-gear in order that the tools may be adjusted up to and away from the work without loosening the set-screws holding them in their sockets. To adjust the shaft, it is simply necessary to revolve nut *w* by means of its hand-wheel, as is obvious, and to lock the nut *w* in its adjusted position the wheel-binding nut *y* is screwed on the projecting end of the screw *t* and caused to jam against said nut *w*. To rotate the worm-gear and through it the tool-shaft, I employ a worm *z*, carried by a shaft *a'* and journaled in suitable bearings on the frame *c*, and this shaft *a'* carries a driving-pulley *b'* on its projecting end. The worm-gear and worm are desirably inclosed, as shown, in suitable housings.

At each end of the bed is arranged a suitable belt-tightener whereby the proper tension to the belt may be given irrespective of the position of the head-stock on the bed.

One of these belt-tighteners is shown in Figs. 1 and 2. This device consists, essentially, of an arm *c'*, attached at its lower end to a horizontal shaft *d'*, journaled in suitable bearings at the end of the bed and carrying at its upper end a pair of idle pulleys *e'*, journaled on suitable stub-shafts carried on the respective ends of a bar *f'*, which is pivoted midway its length in the upper end of arm *c'*. Attached to shaft *d'* is a segmental worm-gear *g'*, and journaled in suitable bearings adjacent to this segment and engaging therewith is a worm *h'*. By means of this worm and worm-gear the arm *c'* may be adjusted vertically and be locked in any of its positions. The pulleys *e'* are supported in alignment with the pulley *b'* on the shaft *a'* and also in alignment with the driving-pulleys *i'*. The driving-belt has its lower part passed over the lower one of the pulleys *e'* and its upper part over the upper pulley, as shown in dotted lines in Fig. 1, these pulleys serving to prevent the oppositely-traveling parts of the belt from impinging against each other and at the same time keep the proper tension on the belt. By pivotally supporting the bar *f'*, carrying the pulleys *e'*, these pulleys automatically adjust themselves as the arm *c'* is raised or lowered to accommodate the varying distances of the head-stock from the end of the bed.

Having thus fully described my invention, what I claim, and desire to secure by Letters Patent, is—

1. In a lathe, the combination of a bed, a head-stock thereon, an endwise-movable shaft journaled on the head-stock frame, this shaft carrying at one end the tool-holders and having its other end provided with a threaded axial extension, a worm-gear secured to said shaft and journaled in the frame of the head-stock and held against endwise movement therein, means for turning said worm-gear, a shell or casing attached to the worm-gear and having a central opening through which the threaded extension of the shaft projects, a nut engaging said casing or shell and threaded on said threaded extension, and a binding-nut, whereby the shaft of the head-stock may be endwisely adjusted, for the purpose set forth.

2. In combination, a bed, a head-stock frame, an endwisely-movable shaft journaled therein and carrying at one end the tool-holders, a gear journaled in the head-stock frame and having a hollow hub through which the other end of said shaft slidably extends, means for causing the gear to rotate with the shaft, means for securing the gear against endwise movement in its bearing, a threaded extension carried by said shaft, a nut on said extension and means for rotatably supporting said nut on the gear, means for turning said gear.

3. In combination, a bed, a head-stock, a gear journaled thereon and held against endwise movement therein, said gear having an

opening in its hub, the tool-shaft journaled in the head-stock frame and having one end slidably working in the hub of the gear, means for endwise adjusting said shaft said 5 means being supported from the gear, and means for operating said gear.

In testimony whereof I hereunto affix my

signature, in the presence of two witnesses, this 12th day of December, 1902.

WILLIAM CLARK KIRK.
